UNITED STATES PATENT OFFICE

2,464,093

FOUNDATION GARMENT

Jack J. Lo Cascio, Bayonne, N. J., assignor to
Even-Pul Foundations, Incorporated, New
York, N. Y., a corporation of New York

Application January 7, 1947, Serial No. 720,570

2 Claims. (Cl. 2—30)

1

This invention relates to an improved foundation garment of the combined brassière and girdle type, and has for its primary object the provision of a garment of this type having a novel and distinctive construction and certain desirable characteristics.

The invention particularly contemplates the provision of a garment of the type indicated which acts to flatten the diaphragm, to support and restrain the abdomen by means of a specially designed internal belt, to control the waistline and avoid unsightly bulging of the body, and to confine surplus flesh of the body without interfering with the freedom of movement of the wearer.

The invention further contemplates a garment of the type indicated which includes a brassière section that gives support and a natural contour to the breasts.

The exact nature of the present garment will become apparent from the following description when considered with the accompanying drawings, in which;

Figure 1 is a front elevational view of a foundation garment constructed in accordance with the present invention, and showing the garment as it appears while being worn.

Figure 2 is a side elevational view thereof.

Figure 3 is a rear elevational view of the same.

Figure 4 is a vertical section taken on line 4—4 of Figure 2.

Figure 5 is an enlarged fragmentary vertical section taken through the front of the garment on line 5—5 of Figure 1.

Figure 6 is a view similar to Figure 5 taken on line 6—6 of Figure 1.

Figure 7 is an enlarged fragmentary horizontal section taken through the front of the garment on line 7—7 of Figure 1.

Figure 8 is a fragmentary rear view of the garment showing the rear closure for the upper part of the girdle section in opened condition.

Figure 9 is a fragmentary elevational view showing the fagoting for connecting adjacent edges of the garment sections and adjacent edges of parts of the girdle section.

Referring in detail to the drawings, the present garment consists of a brassière section B, and a girdle section G joined at the upper edge of its front portion and parts of its side portions to the lower edge of the brassière section by fagoting 5 so as to permit free relative flexing of the sections and to promote ventilation.

The brassière section includes breast pockets

2

6 joined along their adjacent or inner side edges, free end band portions 7 joined to the outer side edges of the pockets 6 and adapted to be adjustably connected by suitable means 8 at the back of the wearer, and elastic breast supporting and separating straps 9 extended entirely across the lower portions of the pockets 6. The pockets are mainly composed of netting or loosely woven fabric and have inserts 10 of closely woven fabric in the lower inner side portions thereof. Shoulder straps 11 connect the tops of the pockets 6 with the rear end portion of the band portions 7.

The girdle section includes a central inelastic 15 front panel 12 of substantially triangular shape disposed with its apex at the bottom, front elastic panels 13 joined to the side edges of the panel 12, and a combined back and side panel 14 of elastic material having its side edges joined to the outer 20 side edges of the panels 13 by fagoting 15 to promote vertical flexibility and ventilation. The panels 13 and 14 include short upper portions and longer lower portions joined by fagoting 16 to further promote flexibility and ventilation. The panels 13 and 14 are yieldable horizontally so as to have a confining action in respect to the girth of the body.

The upper part of the panel 14 is slit centrally of 30 the back thereof to provide a partial closure which aids in donning the garment, suitable means such as a slide fastener 17 being provided to close and secure the closure in closed condition.

On the inside of the front portion of the girdle 35 section is a confining belt that extends nearly the full length of said front portion and consists of a central inelastic panel 18 of triangular form and elastic laterally yieldable side panels 19 joined at their inner edges to the side edges of the panel 18 and at their outer edges to the panels 13 intermediate the side edges of the latter and along downwardly converging lines. The panel 18 has its apex at the bottom, and inelastic fabric strips 20 are stitched to the outer faces of the panels 13 along and by the downwardly converging lines of stitching 21 which secure the outer edges of the belt panels 19 to the panels 13. This arrangement provides a peculiar desirable control or confining action on the abdomen and diaphragm and allows comfortable movement and breathing of 50 the wearer of the garment.

From the foregoing description, it is believed that the advantages and novel features of the invention will be apparent. Changes in details of construction are contemplated, such as fall within 55 the scope of the invention as claimed.

What I claim is:

1. A foundation garment including a girdle section, and a brassière section joined at the lower edge of its front portion to the upper edge of the front portion of the girdle section by fagoting, the remainder of the brassière and girdle sections being free of each other, said girdle section comprising a central front inelastic panel of triangular form and disposed with its apex at the bottom of the panel, horizontally yieldable elastic front panels joined to the side edges of said inelastic panel, a combined back and side panel of horizontally yieldable elastic material joined at its side edges to the outer side edges of the front elastic panels by fagoting, and downwardly converging inelastic fabric strips secured to the outer faces of the front elastic panels intermediate the side edges of the latter and in spaced relation to the sides of said central front panel. 15
2. The construction defined in claim 1, in combination with a belt on the inside of the front portion of said girdle section extending nearly the full length of the latter, said belt including a cen- 20

tral inelastic triangular panel disposed with its apex at the bottom of the panel, and downwardly converging laterally yieldable elastic panels joined to the side edges of the central panel of the belt and attached at their outer edges to the front elastic panels of the girdle section coincident with said downwardly converging fabric strips.
